Primary Examiner — Wan Laymon*Assistant Examiner* — Clint A Samuel(74) *Attorney, Agent, or Firm* — Wolf, Greenfield & Sacks, P.C.(57) **CLAIM**

The ornamental design for a delivery case, as shown and described.

DESCRIPTION

FIG. 1 is a front, bottom, right side, perspective view of a delivery case showing our new design in an open configuration;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front, bottom, right side, perspective view of the delivery case in a closed configuration;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof; and,

FIG. 14 is a bottom plan view thereof.

The dash-dash broken lines represent portions of the delivery case that form no part of the claimed design. The dot-dash broken lines shown represent boundaries of the claimed design and form no part thereof.

1 Claim, 10 Drawing Sheets(56)
